TORQUE LIMITING SPRAG MECHANISM
 Johan Lund, Detroit, Mich., assignor to Formsprag
 Company, Warren, Mich., a corporation of Michigan
 Original No. 3,094,195, dated June 18, 1963, Ser. No.
 36,961, June 17, 1960. Application for reissue Jan. 6,
 1964, Ser. No. 344,800

29 Claims. (Cl. 188—82.2)

Matter enclosed in heavy brackets [ ] appears in the original patent but forms no part of this reissue specification; matter printed in italics indicates the additions made by reissue.

The present invention relates to an improved torque limiting mechanism incorporating a sprag clutch type device and, more particularly, to a torque limiting sprag mechanism by which input torque in either rotative direction transmitted, preferably directly to an output member, may be reliably limited, so as to prevent the arising of damaging or destructive stress in any part of the mechanism.

It is an object of the invention to provide a mechanism of this sort which contains a sprag clutch type locking device characterized by one or more sets of sprag elements, there being in the illustrated embodiment a pair of sprags in each set, with the respective sprags of the set oriented oppositely of one another whereby, depending upon the direction of rotation of an inner input member upon which the sprags are carried, one of the same may be shifted, in response to the arising of a torque in the mechanism exceeding a predetermined value, into locking engagement with a fixed race, thereby preventing the building up of any further torsional stress in the mechanism.

Another object is to provide a sprag type torque limiting mechanism, as described, in which all sprags of the several sprag sets are normally urged resiliently in a direction to place and maintain the same out of the aforesaid locking and torque limiting engagement with a fixed race, being displaced from that position by control fingers which come into action when a predetermined torsional stress is exceeded.

Yet another object is to provide a sprag mechanism of the class described, characterized by sprags shifted by control elements or fingers into locking engagement with a fixed race, upon the building up of a predetermined torsional stress in the line of power transmission from input to output, in which the sprags and fingers are nevertheless rotatable freely in either direction relative to a concentric outer fixed locking race, with radial clearance relative to the latter, under any degree of torsional loading less than said predetermined value. Instantaneous setting and resetting in either rotative direction are thus possible.

Above the predetermined value referred to a relative rotative shift of the control members or fingers and the sprags causes the latter to be tilted into a wedging and locking engagement with the outer locking member or race as an anchor, thus to prevent further torsional stress within the mechanism, or the line of torque transmission from input to output.

Another general object is to provide a sprag torque limiting mechanism operating as described, which is of extremely simple and rugged structural character, and is capable of operating efficiently under extremely severe conditions, such as of vibration and the like.

A still further object is to provide a sprag type torque limiting mechanism operating in accordance with the foregoing principles, in which special provision is made to control or discipline possible high frequency vibratory action or chatter in operation, as in the event the mechanism is employed in the adjustable control of a device,

such as an airplane elevator flap or the like, subject to considerable vibration in normal use.

In accordance with one embodiment having this objective, the invention contemplates the stabilization of the sprags by the use of individual control fingers separating the sprags which constitute an oppositely oriented pair, in addition to control fingers separating successive oppositely oriented pairs, as in the broader aspect of the invention. This assures a complete bi-directional control and disciplining of the sprags by the fingers against vibratory chatter in operation.

In accordance with an alternative embodiment having the objective of eliminating possible vibratory sprag action, the invention contemplates the use of an additional 15 freely floating control ring having spacer bars projecting axially into the spaces, not only between successive oppositely oriented sprag pairs (as the control fingers proper of the member project), but also into the spaces between individually oppositely oriented sprags constituting such 20 pairs. The result is that the freely floating ring serves as an agency by which the sprags are at all times engaged to stabilize and discipline the same against high frequency 25 vibratory chatter. In this connection, the bars in question are employed, when one sprag of a pair is in an engaged, locking position, to urge the other sprag of the pair against the action of the spring which holds it in a normal disengaged position, to an even more fully disengaged position, in which the spring exerts augmented force to hold such disengaged sprag against the vibratory 30 chatter.

It is evident that, in consequence of the improved means for controlling the disengaged sprags against vibratory action, insurance is had that all such sprags will be positively held in a position to re-engage and lock the 35 mechanism when the torsional stress on its torque rod is such as to so demand.

The foregoing as well as other objects will become more apparent as this description proceeds, especially when considered in connection with the accompanying 40 drawings illustrating the invention, wherein:

FIG. 1 is a fragmentary view in transverse section, along a line corresponding to line 1—1 of FIG. 2, of a torque limiting mechanism in accordance with one embodiment of the invention;

FIG. 2 is a fragmentary view in section along broken line 2—2 of FIG. 1;

FIG. 3 is a fragmentary, enlarged scale view similar to FIG. 1, more clearly depicting the operation of the mechanism;

FIG. 4 is a somewhat schematic perspective view, partially broken away and in axial section, showing a typical application of the principle of the invention to a positioning device;

FIG. 5 is a fragmentary view in section similar to FIG. 3, illustrating components of a torque limiting mechanism operating in the manner of the embodiment of FIGS. 1—4, but additionally equipped to control its sprags against excessive vibratory action, hence to positively insure their simultaneous locking engagement when desired;

FIG. 6 is a fragmentary view in section similar to FIG. 2, showing a further anti-friction embodiment featuring augmented control through the agency of a special floating washer or ring carrying control bars;

FIG. 7 is a fragmentary enlarged scale view in transverse section along a line corresponding to line 7—7 of FIG. 6; and

FIG. 8 is a fragmentary elevational view further illustrating the bar-carrying control ring or washer appearing in FIGS. 6 and 7.

First referring to FIG. 4 of the drawings showing an application of the subject mechanism to a positioning device as being illustrative of many different applications to

which the invention is suited, the reference numeral 10 designates a worm gear or pinion which may be assumed to be rotatably actuated through meshing engagement with the worm 12. This type of irreversible drive unit, or its equivalent, is to be preferred for certain uses of the torque limiting mechanism of the invention, generally designated 14; however, other uses do not impose such requirement or even desirability. Hence it is to be understood that the member 10 may be otherwise actuated, directly or through appropriate means drivingly connected hereto in the manner of the worm 12, for example.

As shown in FIG. 4, the worm gear or pinion 10 has a fixed spline driving connection at 16 to one end of an elongated torque rod 18 coaxial therewith; and the torque rod 18 is also drivingly connected to a tubular output member 20. A spline connection 22 is appropriate for the purpose.

The tubular output member or sleeve 20 is shown in FIG. 4 as carrying an integral operating arm or crank 4, the function of which may be assumed to be that of positioning a part, such as an airplane aileron, elevator or stabilizer, in response to rotative manipulation of the worm pinion 10 or equivalent member, yet without imposing any excess of a predetermined torque on the parts in its operation.

In order to attain this objective, the member 10 is shown as fixedly connected rigidly, preferably integrally, to an inner annular race 26 of the torque limiting mechanism 4, the nature of which is hereinafter described in greater detail. Torsion rod 18 extends coaxially through the inner bore 28 of race 26, and the latter has a reduced diameter, cylindrical shoulder 30 which pilots within the bore of tubular member or sleeve 20.

The race 26 is journaled between the pilot shoulder 30 and its splined connection to member 10, as by means of ball bearing 32, the outer race 34 of which is fixed within an internal annular recess 36 at one axial end of an outer race 38. This outer race is a fixed one presenting an internal cylindrical race surface 40 adapted to be engaged by the sprags of the mechanism 14, in a manner to be described; and these sprags are carried, in a manner also to be described, on an outer surface 42 of the inner race 26.

In order to complete the anti-friction bearing provisions of the installation, the tubular member of sleeve 20 is journaled within an annular recess 44 of fixed race 38, as by a further ball bearing 46, whose inner race surrounds the sleeve.

Now referring to FIGS. 1, 2 and 3 in conjunction with FIG. 4, the tubular member or sleeve 20 is integrally formed, or otherwise constituted, to provide a plurality of equally spaced control fingers 48 extending axially inwardly of the anti-friction bearing 46 for the sleeve, the sleeve this end carrying a radially outwardly extending flange 49 upon which the fingers 48 are formed to extend into the annular space between bearings 32, 46 and races 26, 38. As shown in FIGS. 1 and 3, the fingers are of truncated, generally triangular section; and they and the flange 49 which carries the same are externally arcuate in a radius slightly less than that of the outer fixed race surface 40, for a free running clearance in the outer race.

The control fingers 48 extend axially inwardly, as shown in FIG. 1, between successive circumferentially spaced sets or pairs of sprags 50, 51, these sprags each having an inner end 52 of generally semi-cylindrical cross sectional outline socketed in a recess or seat 53 of similar outline in the inner race 26, there being sufficient clearance at the outer periphery 42 of this race to permit free pivoting of the sprag in the socket seat 53.

The sprags 50, 51 are of like cross sectional outline, and are oriented in each pair or set oppositely of one another, as best shown in FIG. 3. Thus, each sprag has an outer wedging surface 54 of a known contour adapted to engage and wedge against the outer sprag race surface 40 and thus lock the inner race against further rotation;

however, the surface 54 of the sprag 50 is so engaged by a clockwise movement about its socket pivot, while the sprag 51 is thus engaged by a counterclockwise movement, in each case from the solid line to the dotted line position appearing in FIG. 3.

The sprags of each pair are urged to the solid line position, withdrawn from engagement with the fixed outer race 40, in any suitable means, and typically by an annular coiled garter spring 56 extending through central apertures in the sprags and engaging edges 58 of such apertures in a manner to exert the desired tilting force, i.e., counterclockwise as to sprag 50 and clockwise as to sprag 51. Provisions of this sort are known to the art, and it will be appreciated that the single garter spring 56 has its equivalent in dual garter springs acting at opposite axial end sprag recesses, and the like.

The significant feature is that such spring means normally urges the sprags of the respective sets simultaneously out of position for wedging engagement with the fixed race, rather than into such position. As illustrated in FIG. 3, when the sprags 50, 51 are in their solid line position the spring 56 will lie over the radially inner surface of sprag opening 57 in such manner as to exert no further effort on the sprag to further tilt it in this direction, i.e., to hold the sprag in its normal solid line position and circumferential spacing relative to an adjacent finger 48, as will be described.

In the normal position of the sprags 50, 51 and the fingers 48 on either circumferential side of a sprag pair, in which position the sprags and fingers normally rotate as the control or operating member 24 is rotated, the circumferential spacing of either sprag 50 or 51 from a finger 48 at one side thereof is quite slight. Thus it is contemplated that a relative motion in either direction of, say, $5\frac{1}{2}^\circ$, depending upon the direction of motion, will result in a sprag 50 or 51 being in engagement with an adjacent finger. Such engagement is the consequence of a build-up of torque in torsion rod 18 and connected parts in excess of a predetermined value, and has the attendant result to be described. However, this relative spacing is subject to change, in accordance with the desired torque limiting characteristic intended for any given use.

In operation, let it be assumed that a manual or other force is applied to operating worm 12 with the intent of predeterminedly rotating worm pinion 10 and, through torsion rod 18 and spline connections 16 and 22, of rotating the control or positioning arm or crank 24 fixed to sleeve 20. Inner race 26 rotates with worm pinion 10 as a part thereof, carrying the sets of retracted sprags 50, 51 therewith, and normally the torsion rod 18 similarly rotates the sleeve 20 and arm or crank 24, whereby the latter locates or positions as desired a further part (not shown) connected thereto.

However, if undue resistance to the last named motion is presented, the torsion rod 18 will yield angularly, with the result that the inner race 26 will rotate slightly relative to the control fingers 48 on sleeve 20, as the latter is subjected to the mounting load through arm or crank 24. If the resistance to motion of the latter continues (assuming that the direction of torque on inner race 26 is in the direction indicated by the arrow in FIG. 3), the sprag 51 will be brought into engagement with the finger 48 to its right, after an extremely small clearance travel referred to above, in a relationship of the sprag and finger suggested in dotted line in FIG. 3 (although it is to be understood that it is the sprag, rather than the finger, which in this instance partakes of the motion, as appears to be the case in that figure). Obviously, when the direction of torque on inner race 26 is the opposite, it will be the other sprag 50 which is brought into engagement to the left with an adjacent finger 48.

The consequence in either case is that the sprag 50 or 51 is tilted from its solid to its dotted line position

of FIGS. 1 and 3, bringing its wedging surface 54 into wedging engagement with the fixed race surface 49. After this, the sprag acts as a rigid post or column locking inner race 26 against further angular motion, and thus preventing the build-up of further torque in torsion rod 18, sleeve 20, operating arm 24 and in other torque sustaining parts connected to the latter. Immediately the torque load is diminished, the sprag 50 or 51 recedes from engagement with the adjacent finger 48, and the spring 56 instantaneously returns the sprag (counterclockwise as to sprag 50 and clockwise as to sprag 51) to its retracted solid line position out of engagement with the fixed locking race 38.

It may be seen from the above that the mechanism 14 will also limit undesired feed back of torque through the same, for example, onto the irreversible operating worm 12. The only difference is that, when the predetermined minimum torque value arises, torsion rod 18 will twist in the angular direction opposite that involved in the above described operation, the fingers 48 will move the slight clearance space to bring them into engagement with the adjacent sprag 50 or 51, and the latter will be tilted (clockwise as to sprag 50 and counterclockwise as to sprag 51) to the dotted line wedging and locking position shown in FIG. 3. Thereafter, no further torsion is imposed on rod 18, nor torque transmitted to or through worm pinion 10 or its equivalent; and the wedged sprag acts as a rigid post or column sustaining further thrust in torque.

While the illustrated embodiment of the invention, featuring an internal, rotatively adjustable sprag socketing race 26 and a fixed outer wedging and locking race 38, is a very efficient and compact one, it is to be understood that in these respects the mechanism of the invention may be reversed, employing suitable provisions including a torque rod coupled to a rotatively adjustable outer race and locked in the event of excessive torque against a fixed inner race. Furthermore, the torque rod 18 may find its equivalent in a flat leaf spring or in a torsion spring, depending on load limiting specifications.

It is seen that the torque limiting mechanism of the invention is very simple, rugged and inexpensive as to its parts. As indicated above, the degree of rotation necessary to lock the sprags is slight, and in this respect the mechanism may be easily engineered to present any desired torque limiting characteristic.

In any design, it is to be understood that under torsion stress on the torque rod 18, or equivalent device, which is less than the predetermined allowable maximum, the control fingers 48 and sprags 50, 51 are carried by the inner race 26 freely and with radial clearance relative to the outer locking race, with the sprags urged by spring 56 to the position shown in solid line in FIGS. 1 and 3, so that instantaneous setting and resetting of arm 24 under a torsional stress less than the designed maximum are possible.

Certain installations of the torque limiting control of the invention subject the same to extreme or high frequency vibration in use, an example being an installation controlling the bi-directional, torsionally limited setting of an airplane wing flap. In order to have positive assurance that all sprags of the respective reversely oriented sets or pairs of the mechanism shall take simultaneous locking engagement with the fixed race, from which they are normally spaced radially in the usual setting and resetting manipulations of the mechanism, the invention contemplates alternatives having augmented vibration inhibiting and disciplining means such as are shown in the embodiments of FIG. 5 and of FIGS. 6-8, respectively.

In these adaptations, a representation of the garter spring corresponding to the annular spring 56 has been omitted for added simplicity; however, it is to be understood that the spring or equivalent means has the identical function of normally maintaining the locking sprags disengaged from and in radially spaced relation to the locking

race. Indeed, the embodiments of FIGS. 5 through 8 incorporate features having an action whereby the spring action is availed of in augmented degree for the vibratory or chatter inhibiting or disciplining effect.

As illustrated in FIG. 5, the assembly is generally similar to that of the first embodiment, including the provision of control members or fingers 60 carried by a member (not shown) corresponding to the flange 49 of the tubular output member 20, and extending axially between successive sets or pairs of reversely oriented sprags, each such set comprising two sprags 61, 62 normally urged in opposite circumferential directions by a garter spring (not shown) disposed in recesses or apertures 63 formed in the respective sprags.

It will be noted in FIG. 5 that the circumferential clearance between successive control fingers 60 and the respective sprags 61, 62 is less than as appears in FIGS. 1 and 2. However, it is to be understood that the embodiment of FIG. 5, like the embodiment of FIGS. 1-4, is reliant upon the use of a torque rod (not shown) corresponding to the torque rod 18 rotatively locked at one end to the tubular member 20 and at the other end to the rotative sprag race 26; and that the locking action of the embodiment of FIG. 5 follows a predetermined stressing of such torque rod sufficient to enable the fingers, moving in one rotative direction or the other, to shift the respective sprags 61, 62 against the outer locking race, here designated 64.

For the purpose of affording augmented anti-vibration control, the embodiment of FIG. 5 employs an auxiliary set of control fingers or bars 65 on the member carrying the same and the fingers 60, these auxiliary members alternating with the control fingers 60 and being positioned equidistant between the same to extend axially between the sprags 61, 62 of each oppositely oriented pair, with slight circumferential clearance relative to the rounded sprag surface 66 facing the auxiliary control members 65. Thus, upon building up of excessive torque in the torque member corresponding to the torque rod 18, in either an angular sense, one of the sprags 61, 62 will be engaged by primary control finger 60, and will be shifted angularly from a normal neutral disengaged position in respect to the locking race 64, represented for example by a dot-dash line "A" running from the axis of tilting movement of the sprag through its wedging point, to a wedging position corresponding to the dot-dash line "C." In so shifting, the sprag 61 or 62 in question will, through the auxiliary control member or finger 65, shift the other sprag of the pair from the normal neutral position "A" to an extreme withdrawn or release position corresponding to the dot-dash line "B." It will be noted that in order to accommodate this extreme shift, the shape of the sprags 61, 62 is modified somewhat, by comparison with those of the first embodiment, in that inwardly of the curved surface 66 there they are recessed circumferentially more deeply at 67, so as to receive the adjacent edge of the respective auxiliary control fingers or members 65.

Thus the released sprag is held against the member or finger 65 under an augmented spring bias due to its being shifted to the extreme position "C." As so held, objectionable vibratory action or chatter is impossible, and it is insured that, when the excessive torsional stress is removed, all released sprags will simultaneously return to neutral position. By the same token, all corresponding sprags will be simultaneously and uniformly engaged to lock the mechanism when an excessive torque arises, in either direction.

The embodiment of the invention illustrated in FIGS. 6, 7 and 8 utilizes components which are in essence identical to those of the embodiment of FIGS. 1 through 4; hence for simplicity corresponding components will be designated by corresponding reference numerals, primed and extended description will be dispensed with.

Thus, as compared with FIGS. 2 and 4 of the drawings, there is a tubular output member 20' having an annula

ge 49' carrying the primary, axially extending control fibers or fingers 48', which, as in the first embodiment, nd between the axially spaced pairs or sets of sprags 51' carried by a bi-directionally rotative inner race and engageable with a fixed outer race 40'; and the ue limiting action of these components is exactly as ribed in connection with FIGS. 1 through 4.

However, in order to contain and discipline vibratory on of the sprags 50', 51', and thus insure uniform and ultaneous locking engagement and disengagement eof in unitary sets, the embodiment of FIGS. 6-8 em- 5 s a special auxiliary annular washer or ring 70. 10 In the form illustrated in FIGS. 6, 7 and 8, the control her or ring 70 is shown as a sheet metal stamping; 15 though it will be appreciated by those skilled in the art the ring may be a machined piece. As embodied in amping, ring 70 floats in the annular space between bi-directional inner race 26 and the fixed locking race moving angularly essentially only in response to en- 20 gement by certain sprags 50', 51', and responding to engagement to move the other of the respective ings.

o these ends, the control ring 70 is formed to provide ries of axially extending bars 73 of substantial circumferential extent, which are slit and offset from the 25 circular flat, radially extending ring body 74. These bars are spaced equidistantly from one another about the 30 ring 70, and successive bars 73 are spaced by secondary 35 bars 75 equidistant therebetween. Secondary bars 75 are reck from the radial body 74 of the ring at a radial 40 distance from the axis thereof to position them for en- 45 gagement with the rounded heel surface 76 of the respective sprags 50', 51'. Similarly, the bars 73 are engage- with an opposite, axially extending surface of each 50 ing at a radially more inward point.

The sprags 50', 51' are socketed in the inner race as ribed in connection with FIG. 1; and as indicated ve, they are actuated for locking engagement with d race 40' to anchor against further torsional stress on parts in the same way. Thus, for the purpose of the inaining description of the embodiment of FIGS. 6, 7 55 and 8, the primary sprag control fingers 48' may be con- 60 nected without reference to the primary torque limiting tion thereof, and this factor may also be dismissed in 65 reference to the function of the respective primary and 70 secondary anti-vibration control bars 73 and 75.

Assuming that torque is applied to the inner race 26' 75 cause the sprags 51' to contact the control members or 80 fingers 48' connected by tubular member 20' to the torque (not shown), this will cause the fingers 48' (assum- 85 the movement is counterclockwise in FIG. 7) to move 90 sprags 51' against the respective control bars 75, 95 which will in turn shift to engage the respective other 100 sprags 50'. In this operation, the control fingers 48' 105 move the sprags 51' toward locking engagement with fixed 110 race 40'; and the other sprags 50' are moved further 115 from their neutral disengaged position shown in 120 line in FIG. 7. So positioned, the control finger 125 is actually working against two sprags, through the 130 agency of bar 75, and is therefore, opposed by twice the 135 mal energizing force of the garter spring. This tends 140 to discipline and limit vibration action of the sprags 145 en it is important that all thereof engage the outer 150 race 40' at the same time.

Any further movement of the basic control fingers 48' 155 will cause all of the sprags 51' to engage and lockingly 160 hinge or anchor against race 40', and will also move the 165 other, oppositely oriented sprags 50' of each pair still 170 further away from the outer race, augmenting the anti- 175 slitter confinement of the latter. In the reverse direction 180 setting movement of inner race 26', the reverse action 185 es place, as regards the respective sprags 50' and 51'. FIG. 7, just as in FIG. 5, the characters "A," "C" and 190 ' indicate positions of a theoretical line through the 195 s of tilt of the sprags upon inner race 26' and the

point of sprag wedging engagement in, respectively, the normal and neutral retracted position of the sprag from outer race 40', its position of wedged engagement with that race, and its extreme released position.

It is seen that the arrangement of FIGS. 6, 7 and 8 5 provides an alternative to that of FIG. 5, by which the sprags, entirely free-moving in the normal unstressed condition of the mechanism, are at all times positively maintained in proper location to simultaneously take locking engagement with the outer race, and, as regards the non-engaged sprags, to prevent objectionable high frequency vibration thereof. Clearances between the respective bars 73, 75 of auxiliary control washer or ring 70 are such as to allow the sprags 50', 51' to operate freely in any direction or position of normal adjustment of the mechanism. Ring 70 is then controlled by the sprag movement, and the established relationship is always maintained between it, the sprags, and the basic control fingers 48'.

In accordance with the invention, it is important to have some degree of lost motion in the action of the various control fingers for the sprags, permitting, say, $6\frac{1}{2}^\circ$ of arcuate travel between the start of movement thereof and the final locking engagement of the sprags with the outer locking race. In some instances, normal manufacturing clearances will permit adequate lost motion. In any instance, the torque rod 18 or 18' may be designed to afford the desired free movement.

What I claim as my invention is:

1. A torque transmitting and limiting mechanism, comprising a pair of coaxial, axially telescoped race members, one of which is rotatively fixed and the other of which has at least limited rotatability about the axis of said members, and means operatively connected to the last named member to so rotate the same only under torque applied thereto not exceeding a predetermined value, said last named means comprising a first power member having a rotatively fixed drive connection to said rotative race member, a second power member having means including a flexible torsion element drivingly connecting the same to said first power member, said first and second power members being rotatable as a unit up to a predetermined value of torque stressing of said torsion element, and means engaging between said race members to lock said power members against rotation under a torque stress on said element in excess of said predetermined value.

2. A torque transmitting and limiting mechanism, comprising a pair of coaxial, axially telescoped race members, one of which is rotatively fixed and the other of which has at least limited rotatability about the axis of said members, and means operatively connected to the last named member to so rotate the same only under torque applied thereto not exceeding a predetermined value, said last named means comprising a first power member having a rotatively fixed drive connection to said rotative race member, a second power member having means including a flexible torsion element drivingly connecting the same to said first power member, said first and second power members being rotatable as a unit up to a predetermined value of torque stressing of said torsion element, means predeterminedly rotating with said second power member and torsion element upon torque flexure of the latter, and means controlled by said predeterminedly rotating means to engage between said race members to lock said power members against rotation under a torque stress on said element in excess of said predetermined value.

3. A bi-directional torque transmitting and limiting mechanism, comprising a pair of coaxial, axially telescoped race members, one of which is rotatively fixed and the other of which has at least limited rotatability about the axis of said members, and means operatively connected to the last named member to so rotate the same in either angular direction only under torque applied thereto not exceeding a predetermined value, said last named means comprising a first power member hav-

ing a rotatively fixed drive connection to said rotative race member, a second power member having means including a flexible torsion element drivingly connecting the same to said first power member, said first and second power members being rotatable bi-directionally by said first power member as a unit up to a predetermined value of torque stressing of said torsion element, and means engaging between said race members to lock said power members against rotation under a torque stress on said element in excess of said predetermined value.

4. A torque transmitting and limiting mechanism, comprising a pair of coaxial, axially telescoped race members, one of which is rotatively fixed and the other of which has at least limited rotatability about the axis of said members, and means operatively connected at the last named member to so rotate the same only under torque applied thereto not exceeding a predetermined value, said last named means comprising a first power member having a rotatively fixed drive connection to said rotative race member, a second power member having means including a flexible torsion element drivingly connecting the same to said first power member, said second power member being rotatable by and with said first power member substantially as a unit up to a predetermined value of torque stressing of said torsion element, means predeterminedly rotating with said second power member and torsion element upon torque flexure of the latter, and means controlled by said predeterminedly rotating means to engage between said race members to lock said power members against rotation under a torque stress on said element in excess of said predetermined value.

5. A torque transmitting and limiting mechanism, comprising a pair of coaxial, axially telescoped race members, one of which is rotatively fixed and the other of which has at least limited rotatability about the axis of said members, and means operatively connected to the last named member to so rotate the same only under torque applied thereto not exceeding a predetermined value, said last named means comprising a first power member having a rotatively fixed drive connection to said rotative race member, a second power member having means including a flexible torsion element drivingly connecting the same to said first power member, said first and second power members being rotatable as a unit up to a predetermined value of torque stressing of said torsion element, and means engaging between said race members to lock said power members against rotation under a torque stress on said element in excess of said predetermined value, comprising radially extending sprag elements rotatable with said rotatable race member and tilttable relative thereto, said sprag elements having wedging surfaces at a radial end thereof for wedging and locking engagement with said fixed race member, said wedging surfaces being circumferentially oriented oppositely relative to one another to take said wedging engagement upon tilting of the sprag elements in opposite directions, and control elements fixed on one of said power members and positioned adjacent said sprag elements to tilt the same for said wedging engagement with said fixed race member upon relative rotation of said power members under an excessive torque on said torsion element.

6. A bi-directional torque transmitting and limiting mechanism, comprising a pair of coaxial, axially telescoped race members, one of which is rotatively fixed and the other of which has at least limited rotatability about the axis of said members, and means operatively connected to the last named member to so rotate the same in either angular direction only under torque applied thereto not exceeding a predetermined value, said last named means comprising a first power member having a rotatively fixed drive connection to said rotative race member, a second power member having means including a flexible torsion element drivingly connecting the same to said first power member, said second power member

being rotatable bi-directionally by said first power member as a unit up to a predetermined value of torque stressing of said torsion element and means engaging between said race members to lock said power members against rotation under a torque stress on said element in excess of said predetermined value, comprising at least one pair of radially extending sprag elements rotatable with said rotatable race member and tilttable relative thereto, said sprag elements having wedging surfaces at a radial end thereof for wedging and locking engagement with said fixed race member, said wedging surfaces being circumferentially oriented oppositely relative to one another to take said wedging engagement upon tilting of the sprag elements in opposite directions, and at least one pair of control elements fixed on said second power member and positioned adjacent said sprag elements to tilt the same for said wedging engagement with said fixed race member upon relative rotation of said power members under an excessive torque on said torsion element.

7. A bi-directional torque transmitting and limiting mechanism, comprising a pair of coaxial, axially telescoped race members, one of which is rotatively fixed and the other of which has at least limited rotatability about the axis of said members, and means operatively connected to the last named member to so rotate the same in either angular direction only under torque applied thereto not exceeding a predetermined value, said last named means comprising a first power member having a rotatively fixed drive connection to said rotative race member, a second power member having means including a flexible torsion element drivingly connecting the same to said first power member, said first and second power members being rotatable bi-directionally as a unit up to a predetermined value of torque stressing of said torsion element, and means engaging between said race members to lock said power members against rotation under a torque stress on said element in excess of said predetermined value, comprising at least one pair of radially extending sprag elements rotatable with said rotatable race member and tilttable relative thereto, said sprag elements having wedging surfaces at a radial end thereof for wedging and locking engagement with said fixed race member, said wedging surfaces being circumferentially oriented oppositely relative to one another to take said wedging engagement upon tilting of the sprag elements in opposite directions, means normally urging said sprag elements away from said wedging engagement, and at least one pair of control elements fixed on said second power member and positioned adjacent said sprag elements to tilt the same for said wedging engagement with said fixed race member upon relative rotation of power members under an excessive torque on said torsion element.

8. A torque transmitting and limiting mechanism, comprising a pair of coaxial, radially spaced and axially telescoped races, one of which is rotatively relatively fixed and the other of which has at least limited relative rotatability about the race axis, and means operatively connected to the last named race to so rotate the same only under torque applied thereto not exceeding a predetermined value, said last named means comprising a first member drivingly connected to said rotative race, a second member having means including a flexible torsion element drivingly connecting the same to said first member, said first and second members being rotatable as a unit up to a predetermined value of torque stressing of said torsion element, radially extending sprags wedgingly engageable between said races to lock said members against relative rotation under a torque stress on said element in excess of said predetermined value, and control elements fixed on one of said members and positioned adjacent said sprags to tilt the same for said wedging engagement with said relatively fixed race upon relative rotation of said first and second members under an excessive torque on said torsion element.

9. A torque transmitting and limiting mechanism, comprising a pair of coaxial, radially spaced and axially telescoped races, one of which is rotatively relatively fixed and the other of which has at least limited relative rotatability about the race axis, and means operatively connected to the last named race to so rotate the same only under torque applied thereto not exceeding a predetermined value, said last named means comprising a first member drivingly connected to said rotative race, a second member having means including a flexible torsion element drivingly connecting the same to said first member, said first and second members being rotatable as a unit up to a predetermined value of torque stressing of said torsion element, radially extending sprags wedgingly engageable between said races to lock said members against relative rotation under a torque stress on said element in excess of said predetermined value, said sprags being arranged in sets in which they are circumferentially oriented oppositely relative to one another to take said wedging engagement in opposite directions, and control elements fixed on one of said members and positioned adjacent said sprags to tilt correspondingly oriented sprags hereof for said wedging engagement with said relatively fixed race upon relative rotation of said first and second members under an excessive torque on said torsion element.

10. A torque transmitting and limiting mechanism, comprising a pair of coaxial, radially spaced and axially telescoped races, one of which is rotatively relatively fixed and the other of which has at least limited relative rotatability about the race axis, and means operatively connected to the last named race to so rotate the same only under torque applied thereto not exceeding a predetermined value, said last named means comprising a first member drivingly connected to said rotative race, a second member having means including a flexible torsion element drivingly connecting the same to said first member, said first and second members being rotatable as a unit up to a predetermined value of torque stressing of said torsion element, radially extending sprags wedgingly engageable between said races to lock said members against relative rotation under a torque stress on said element in excess of said predetermined value, said sprags being arranged in sets in which they are circumferentially oriented oppositely relative to one another to take said wedging engagement in opposite directions, control elements fixed on one of said members and positioned adjacent said sprags to tilt correspondingly oriented sprags hereof for said wedging engagement with said relatively fixed race upon relative rotation of said first and second members under an excessive torque on said torsion element, spring means urging all of said sprags out of engagement with said fixed race, and means positively engaging and urging the correspondingly oriented and disengaged sprags in position to said spring means.

11. A mechanism in accordance with claim 10, in which said last named means comprises auxiliary control elements positioned to engage and urge said other sprags in opposition to said spring means.

12. A mechanism in accordance with claim 10, in which said last named means comprises auxiliary control elements positioned to engage and urge said other sprags in opposition to said spring means, said auxiliary elements being fixedly mounted on the member to which said first named control elements are fixed.

13. A mechanism in accordance with claim 10, in which said last named means comprises auxiliary control elements positioned to engage and urge said other sprags in opposition to said spring means, said auxiliary elements being fixedly mounted on the member to which said first named control elements are fixed in alternation with the latter.

14. A mechanism in accordance with claim 10, in which said last named means comprises an annular control member mounted for circumferential floating movement be-

tween said races and provided with auxiliary control elements respectively engageable between oppositely oriented sprags of a set and between sprag sets to maintain engagement with the sprags of said sets in opposition to said spring means.

15. A mechanism in accordance with claim 10, in which said last named means comprises an annular control member mounted for circumferential floating movement between said races and provided with auxiliary control elements respectively engageable between oppositely oriented sprags of a set and between sprag sets to maintain engagement with the sprags of said sets in opposition to said spring means, said relatively rotatably race engaging and carrying said floating annular control member for said last named engagement.

16. A torque transmitting and limiting mechanism, comprising a pair of coaxial, axially telescoped race members, one of which is rotatively fixed and the other of which has at least limited rotatability about the axis of said members, a driver member having means operatively connecting the same to the last named race member to freely rotate the latter under torque applied thereto not exceeding a predetermined value, a driven member, said driver member having a drive connection to operate said driven member which is yieldable under a torque load on the latter in excess of said value, thereby occasioning a relative rotative movement of said driver and driven members, and parts operatively connected in socketed torque receiving engagement with said rotative race member, said parts being engaged by one of said driver and driven members in automatic response to said relative movement thereof under torque in excess of said value to engage said parts with said fixed race member to transmit the excess torque to the latter.

17. A bi-directional torque transmitting and limiting mechanism, comprising a pair of coaxial, axially telescoped race members, one of which is rotatively fixed and the other of which has at least limited rotatability about the axis of said members, a driver member having means operatively connecting the same to the last named race member to so rotate the latter in either angular direction only under torque applied thereto not exceeding a predetermined value, a driven member, said driver member having a drive connection to operate said driven member which is yieldable under a torque load on the latter in excess of said value, thereby occasioning a relative rotative movement of said driver and driven members, and parts operatively connected in torque receiving engagement with said rotative race member, said parts being engaged by one of said driver and driven members in automatic response to said relative movement thereof under torque in excess of said value to engage said parts with said fixed race member to transmit the excess torque to the latter.

18. A mechanism in accordance with claim 1, in which said last named means comprises sprags disposed between said race members, one of said power members having means engaging a sprag to place the same in race engaging and locking position upon relative rotation of said power members due to torsional stressing of said torsion element above said predetermined value, thus to so lock said power members.

19. A mechanism in accordance with claim 1 which is bi-directional in action, in which said last named means comprises sprags disposed in oppositely oriented position, in the circumferential sense, between said race members, one of said power members having means engaging a predeterminedly oriented sprag to place the same in race engaging and locking position upon relative rotation of said power members due to torsional stressing of said torsion element above said predetermined value, thus to so lock said power members, an oppositely oriented sprag being out of race locking position at this time.

20. A mechanism in accordance with claim 1 which is bi-directional in action, in which said last named means comprises sprags disposed in oppositely oriented position,

in the circumferential sense, between said race members, one of said power members having means engaging a predeterminedly oriented sprag to place the same in race engaging and locking position upon relative rotation of said power members due to torsional stressing of said torsion element above said predetermined value, thus to so lock said power members, an oppositely oriented sprag being out of race locking position at this time, and means responsive to said relative rotation of the power members to engage and dampen vibration of said oppositely oriented sprag in said non-locking position of the latter.

21. A torque transmitting and limiting mechanism, comprising a pair of coaxial, axially telescoped race members, one of which is rotatively fixed and the other of which has at least limited rotatability about the axis of said members, a driver member having means operatively connecting the same to the last named race member to so rotate the latter only under torque applied thereto not exceeding a predetermined value, a driven member, said driver member having a drive connection to operate said driven member which is yieldable under a torque load on the latter in excess of said value, thereby occasioning a relative rotative movement of said driver and driven members, and sprags disposed for movement into torque transmitting engagement between said race members, said sprags being engaged by one of said driver and driven members in automatic response to said relative movement thereof under torque in excess of said value to engage said last named sprags in wedging position between said race members to transmit the excess torque to the fixed race member.

22. A bi-directional torque transmitting and limiting mechanism, comprising a pair of coaxial, axially telescoped race members, one of which is rotatively fixed and the other of which has at least limited rotatability about the axis of said members, a driver member having means operatively connecting the same to the last named race member to so rotate the latter in either angular direction only under torque applied thereto not exceeding a predetermined value, a driven member, said driver member having a drive connection to operate said driven member which is yieldable under a torque load on the latter in excess of said value, thereby occasioning a relative rotative movement of said driver and driven members, and sprags disposed for movement into torque transmitting engagement between said race members, said sprags being disposed between said races in oppositely oriented sets in the circumferential sense, sprags of one set being positioned for said torque transmitting wedging engagement while sprags of the oppositely oriented set are not, the sprags of said one set being engaged by one of said driver and driven members in automatic response to said relative movement thereof under torque in excess of said value to place said last named sprags in wedging position between said race members to transmit the excess torque to the fixed race member.

23. A bi-directional torque transmitting and limiting mechanism, comprising a pair of coaxial, axially telescoped race members, one of which is rotatively fixed and the other of which has at least limited rotatability about the axis of said members, a driver member having means operatively connecting the same to the last named race member to so rotate the latter in either angular direction only under torque applied thereto not exceeding a predetermined value, a driven member, said driver member having a drive connection to operate said driven member which is yieldable under a torque load on the latter in excess of said value, thereby occasioning a relative rotative movement of said driver and driven members, and sprags disposed for movement into torque transmitting engagement between said race members, said sprags being disposed between said races in oppositely oriented sets in the circumferential sense, sprags of one set being positioned for said torque transmitting wedging engagement while sprags of the oppositely oriented set are not, the

sprags of said one set being engaged by one of said driver and driven members in automatic response to said relative movement thereof under torque in excess of said value to place said last named sprags in wedging position between said race members to transmit the excess torque to the fixed race member, and means also controlled in response to said relative movement of said driver and driven members to engage the sprags of said oppositely oriented set to dampen vibration thereof.

24. A torque transmitting and limiting mechanism, comprising a pair of coaxial members, one of which is rotatively fixed and the other of which has at least limited rotatability about the axis of said members, a driver having means operatively connecting the same to the last named member to so rotate the latter as a driver member, and a driven member, said driver member having a drive connection to operate said driven member only under torque not exceeding a predetermined value, which connection is yieldable under a torque load in excess of said value, thereby occasioning a relative movement of said driver and driven members, said drive connection including a part operatively connected for torque transmitting engagement with the respective driver and driven members, said part being actuated by one of said driven and driven members in automatic response to said relative movement thereof, under torque in excess of said value, to engage said part with said rotatively fixed member to transmit the excess torque to the latter.

25. A bi-directional torque transmitting and limiting mechanism, comprising a pair of coaxial members, one of which is rotatively fixed and the other of which has at least limited rotatability about the axis of said members, a driver having means operatively connecting the same to the last named member to so rotate the latter as a driver member in either angular direction, and a driven member, said driver member having a drive connection to operate said driven member only under torque not exceeding a predetermined value, which connection is yieldable under a torque load in excess of said value, thereby occasioning a relative movement of said driver and driven members, said drive connection including parts operatively connected for torque transmitting engagement with the respective driver and driven members, said parts being actuated by one of said driver and driven members in automatic response to said relative movement thereof under torque in one angular direction or the other in excess of said value, to engage said parts with said rotatively fixed member to transmit the excess torque to the latter.

26. A torque transmitting and limiting mechanism comprising a pair of coaxial members, one of which is rotatively fixed and the other of which is a driver member having at least limited rotatability about the axis of said members, means to so rotate said driver member a driven member in axially telescoped relation to said rotatively fixed member, and means to rotate said driven member from said driver member only under torque not exceeding a predetermined value, comprising a drive connection to operate said driven member from said driver member under torque beneath said predetermined value, which connection is yieldable under a torque load in excess of said value, thereby occasioning a relative rotative movement of said driver and driven members, said drive connection including a part operatively connected for torque transmitting engagement with the respective driver and driven members, said part being actuated by one of said driver and driven members in automatic response to said relative movement thereof, under torque in excess of said value, to engage said part with said rotatively fixed member to transmit the excess torque to the latter.

27. A bi-directional torque transmitting and limiting mechanism, comprising a pair of coaxial members, one of which is rotatively fixed and the other of which is a driver member having at least limited rotatability about

15

axis of said members, means to so rotate said driver member in either angular direction, a driven member axially telescoped relation to said rotatively fixed member, and means to rotate said driven member from said member only under torque not exceeding a predetermined value, comprising a drive connection to operate said driven member from said driver member under torque beneath said predetermined value, which connection is yieldable under a torque load in excess of said value, thereby occasioning a relative rotative movement of said driver and driven members, said drive connection including parts operatively connected for torque transmitting engagement with the respective driver and driven members, said parts being actuated by one of said driver and driven members in automatic response to said relative movement thereof, under torque in one angular direction or the other in excess of said value, to engage said parts with said rotatively fixed member to transmit the excess torque to the latter.

18. A torque transmitting and limiting mechanism, comprising a pair of coaxial members, one of which is rotatively fixed and the other of which is a driver member having at least limited rotatability about the axis of said members, means to so rotate said driver member, a driven member in axially telescoped relation to said rotatively fixed member, and means to rotate said driven member from said driver member only under torque not exceeding a predetermined value, comprising a drive connection to operate said driven member from said driver member under torque beneath said predetermined value, which connection is yieldable under a torque load in excess of said value, thereby occasioning a relative rotative movement of said driver and driven members, said drive connection including parts actuated by one of said driver and driven members in automatic response to said relative movement thereof, under torque in one angular direction or the other in excess of said value, to engage said parts with said rotatively fixed member to transmit the excess torque to the latter.

16

members, said drive connection including a part actuated by one of said driver and driven members in automatic response to said relative movement thereof, under torque in excess of said value, to engage said part with said rotatively fixed member to transmit the excess torque to the latter.

29. A bi-directional torque transmitting and limiting mechanism, comprising a pair of coaxial members, one of which is rotatively fixed and the other of which is a driver member having at least limited rotatability about the axis of said members, means to so rotate said driver member in either angular direction, a driven member in axially telescoped relation to said rotatively fixed member, and means to rotate said driven member from said driver member only under torque not exceeding a predetermined value, comprising a drive connection to operate said driven member from said driver member under torque beneath said predetermined value, which connection is yieldable under a torque load in excess of said value, thereby occasioning a relative rotative movement of said driver and driven members, said drive connection including parts actuated by one of said driver and driven members in automatic response to said relative movement thereof, under torque in one angular direction or the other in excess of said value, to engage said parts with said rotatively fixed member to transmit the excess torque to the latter.
